UNITED STATES PATENT OFFICE.

GEORGE MANN, OF JACKSON, MICHIGAN, ASSIGNOR, BY MESNE ASSIGNMENTS, TO REYNOLDS SPRING COMPANY, OF JACKSON, MICHIGAN, A CORPORATION OF DELAWARE.

ELECTRIC SWITCH.

Application filed November 30, 1925. Serial No. 72,251.

The invention relates to an electric switch.

The object of the present invention is to provide a simple, practical and efficient electric snap switch of the push button type which will be strong and durable and comparatively inexpensive in construction and in which the parts will be securely and firmly held in position so that the liability of the same becoming loose and short circuiting or otherwise becoming inoperative will be reduced to a minimum.

Another object of the invention is to provide a push button snap switch of this character in which the insulating material will be reduced to a minimum and a maximum air space provided around the switch mechanism for increasing the effectiveness of the insulation when the current is interrupted.

With these and other objects in view, the invention consists in the construction and novel combination and arrangement of parts hereinafter fully described illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:

Figure 1 is a side elevation of an electric switch constructed in accordance with this invention.

Fig. 2 is a similar view, one of the sections of the casing or body being removed to illustrate the manner of mounting the switch mechanism.

Fig. 3 is a transverse sectional view of the electric switch, the switch mechanism being open.

Fig. 4 is a longitudinal sectional view of the same, the switch mechanism being closed.

Fig. 5 is a detail view of one of the sections of the hollow body or casing.

Fig. 6 is a detail perspective view of the oblong support.

Fig. 7 is a detail perspective view of the actuator.

In the accompanying drawing in which is illustrated the preferred embodiment of the invention, the electric switch is provided with a hollow body or casing composed of two substantially semi-cylindrical sections 1 and 2 designed to be constructed of molded

bakelite or other suitable plastic insulating material but any suitable material may be employed in the construction of the casing. The sections of the casing form an interior chamber for the reception of the snap switch mechanism and they are provided at their opposite ends with registering recesses 3 forming openings for the passage of the terminal portions of the insulating wire for carrying the current to the switch. The sections 1 and 2 are also provided at opposite sides with central registering notches or recesses 4 for the reception of the push buttons 5 of the actuator 6 of the snap switch mechanism. The sections are secured together by connecting screws 7 having their heads counter-sunk in one of the sections and engaging counter-sunk nuts 8 in the opposite section but the two sections of the hollow body or casing will be secured together in any other suitable manner as will be readily understood.

The section 1 of the casing is provided at one side with spaced enlargements 9 arranged at the end portions of that side of the section adjacent the recesses 3 and recessed at 10 to form seats for stationary blades 11. The enlargements 9 are spaced apart to provide an intervening space or recess 12 to receive an oblong support 13 of the snap switch mechanism and the said enlargements are provided with transverse extensions 14 forming parallel flanges and providing extensions of the walls of the recess 12. The stationary switch blades consist of blades of suitable conducting material bent at right angles to provide attaching portions to the projecting blades which are located at opposite sides of the snap switch mechanism. The attaching portions of the stationary blades are secured in the recesses of the enlargements by means of threaded bushings 15 embedded in the insulating material and having the attaching portions of the stationary switch blades riveted to them and adapted to receive binding screws 16 for securing the terminals of the connecting wires to the stationary switch blades in the usual manner. By embedding the threaded bushings in the insulating material the stationary switch blades are firmly secured to the section 1 of the casing and are securely maintained in proper position with relation to the snap switch mechanism.

The snap switch mechanism comprises in its construction the said oblong support 13,

the actuator 6 and a movable switch member 17 which is fulcrumed on the support and which swings into and out of contact with the stationary switch blades. The oblong support is composed of spaced side and end walls, the side walls being formed integral with one of the end walls and one of the side walls being integral with the other end wall which is unconnected from the other side to form a resilient support adapted to maintain itself firmly in position in the recess or space between the enlargements by its resiliency. The oblong support is formed by bending a plate or strip of sheet metal such as sheet iron at right angles at intervals to form the side and end walls and the sides of the support are compressed in introducing the snap switch mechanism in position in the section 1 of the casing and when pressure is removed from the sides of the oblong support the resiliency or spring action of the sides will firmly hold the snap switch mechanism in position. In order to enable the support to be positively fastened to the section 1 the said support is provided at one side with a laterally extending attaching lug 18 which is perforated for the reception of a suitable fastening device 19 for securing it to the casing 1. The casing 1 is provided adjacent to the lug with an enlargement 20 upon which the lug is seated and which may be provided with a suitable threaded bushing to be engaged by the screw 19.

35 The sides of the support are provided with tapered or V-shaped recesses 21 forming bearings at their apexes for the swinging switch member of the snap switch mechanism. The swinging switch member consists of a yoke and is composed of spaced sides and an outer connecting portion. The sides are provided at their inner ends with laterally extending fulcrumed portions 21 which are arranged in the bearings of the sides of the oblong support. The swinging switch member is provided at the outer ends of its sides with laterally extending contact portions 22 forming extensions of the cross base of the yoke which is adapted to bridge the space between the stationary switch blades and contact therewith. The switch blades are provided at their outer ends with alined inwardly extending transverse contact portions 23 which are arranged in an overlapping position with relation to the swinging switch member to prevent any liability of the movable switch member swinging past the stationary switch blades. The movable switch member is limited in its swing by the walls of the V-shaped recesses of the oblong support.

60 The movable switch member is operated by the actuator 6 consisting of an oblong slide actuated between the sides of the oblong

support and limited in its movement by the end walls of the support and provided with approximately L-shaped shanks 24 to which are attached opposite longitudinally alined push buttons 5 preferably by embedding the shanks in the push buttons constructed of plastic insulating material. The end walls of the support are provided with registering openings 25 in which the push buttons slide and which form guides for the push buttons. The push buttons are designed to be of different colors in order to indicate readily whether the switch is open or closed. The slide is provided at opposite sides with spaced arms 26 arranged in pairs and having inclined inner edges and adapted to engage the sides of the swinging switch member for positively moving the same whereby the switch member is prevented from becoming stuck to the stationary switch blades. The movable switch member is connected with the slide by a coiled spring 27 secured at its outer end in a perforation 28 of the swinging switch member and at its inner end to a perforated lug 29 of the oblong slide. The section 1 of the casing is provided at the side opposite to that at which the enlargements are arranged with inwardly extending flanges 30 which form abutments for the adjacent end of the oblong support. The spring is placed under tension by the movement of the slide and producing a snap action and effects a sudden quick movement of the parts and a quick opening and closing of the switch.

65 What is claimed is:

An electric switch including a hollow insulating casing composed of approximately semi-cylindrical sections, one of the sections being provided with spaced enlargements recessed to form seats and provided with projecting flanges located at the space between the said enlargements and forming continuations of the walls of the said space, said section of the casing being also provided with spaced inwardly extending flanges at its opposite side, stationary switch blades secured in the recesses of the said enlargements, snap switch mechanism comprising an oblong support fitting between the said enlargements and against the flanges at the opposite side of the casing, said support being also provided with a projecting attaching lug adapted to be secured to the casing, a slide operating in the support, a movable switch member fulcrumed on the support and adapted to be carried into and out of engagement with the stationary switch blades, and a spring connection between the slide and the movable switch member.

70 In testimony whereof I have hereunto set my hand.

75 80 85 90 95 100 105 110 115 120 125
GEORGE MANN.
